UNITED STATES PATENT OFFICE.

GODFREY S. SCOVELL, OF TORONTO, ONTARIO, CANADA.

TOOTH-BRUSH HOLDER.

Specification of Letters Patent. Patented June 27, 1916.

1,188,845.

Application filed January 25, 1916. Serial No. 74,258.

To all whom it may concern:

Be it known that I, GODFREY S. SCOVELL, a subject of the King of Great Britain, residing at Toronto, in the Province of Ontario, Canada, have invented certain new and useful Improvements in Tooth-Brush Holders, of which the following is a specification.

This invention relates to tooth brushes and the object of the same is to provide a device whereby a tooth brush of the ordinary shape can be conveniently carried in a garment pocket.

More specifically this invention provides a tooth brush holder including a pair of sections, one a receiver and handle, the other a plug for insertion in one end of said receiver and handle, the plug section having the tooth brush attached thereto so that the brush can be positioned within the receiver and handle or be retained in connection with the same so as to utilize the receiver and handle when the brush is in use.

A still further object of this invention is to provide a tooth brush holder of the kind above described that is simple in construction, efficient in operation and consists of the minimum number of parts.

With these and other objects in view, this invention consists of certain novel constructions, combinations and arrangement of parts, as will be hereinafter fully described and claimed.

In the accompanying drawings: Figure 1 is a view in elevation of the improved device as it is when in use; Fig. 2 is a longitudinal sectional view of the improved device, the parts thereof being shown in a position opposite to that as shown in Fig. 1, the tooth brush being shown in elevation, and Fig. 3 is a section taken on line 3-3 of Fig. 2.

Referring to the parts by reference numerals, 10 designates a handle and receiver section having one end thereof open and in its opposite end a vent 11. The other section of this device is designated in its entirety by the numeral 12, the said section 12 forming a plug for insertion in the open end of the handle and receiver section 10. This plug section 12 has formed at one end thereof a reduced neck 13 the said neck being of such size as to snugly engage the handle of the conventional form of tooth brush. This is clearly shown in Figs. 2 and 3. A bead

14 is formed on the plug section and is adapted to engage the handle and receiver section 10 so as to limit the insertion of the plug section into the section 10. Air vent openings 15 are formed in the plug section 12 in substantial alignment with the vent opening 11 in the closed end of the handle and receiver section 10 thus providing means for the circulation of air in the receiver or handle portion 10 when the device is positioned as shown in Fig. 2.

In use the plug section 12 is inserted in the section 10 as shown in Fig. 1 and the section 10 is used as a handle to apply the bristles of the brush held by the plug section to the teeth. After use of the same the plug section 12 is inserted in the section 10 so as to position the handle of the brush in the section 10 as clearly shown in Fig. 2 and the device when in this position can be carried in the ordinary garment pocket. By having the vent openings arranged as has been heretofore set forth a complete circulation of air is permitted in the section 10 and thus the bristles of the brush will be thoroughly dried when in this position.

It is of course to be understood that the plug section 12 is of such size and the section 10 of such material as to make the frictional engagement of the faces of the plug section 12 and the handle and receiver sections 10 retain the sections in connection. Furthermore there is absolutely no likelihood of the plug section being inserted too far into the receiver and handle section 10 when the said plug section is in either position in that the bead 14 will engage the end of the handle and receiver section.

It is obvious that minor changes may be made in the form and construction of this invention without departing from the material parts thereof. It is therefore not wished to confine the invention to the exact form herein shown and described, but it is wished to include all such as properly come within the scope claimed.

I claim—

In a holder for tooth brushes of conventional form, a handle and receiving section, a second section adapted for insertion into said handle section in either of two positions, a reduced neck extending from one end of said second section open at each end, said neck being so disposed whereby upon reception of the handle of the tooth brush the handle

will lie snugly against the inner wall of said second section, and said second section having means to limit its telescopic movement in the other section when the brush is extended free of or inclosed in the latter section.

In testimony whereof I affix my signature in presence of two witnesses.

GODFREY S. SCOVELL.
